UNITED STATES PATENT OFFICE.

WILLIAM T. BIDDLE, OF WILMINGTON, DELAWARE. ASSIGNOR OF ONE-HALF TO
STANLEY HAMMOND, OF WILMINGTON, DELAWARE.

SAFE AUTOMATIC DRIFTING DEVICE FOR LOCOMOTIVES.

1,251,328.

Specification of Letters Patent. Patented Dec. 25, 1917.

Application filed December 8, 1915. Serial No. 65,833.

To all whom it may concern:

Be it known that I, WILLIAM T. BIDDLE, a citizen of the United States, residing in Wilmington, in the county of New Castle 5 and State of Delaware, have invented new and useful Improvements in Safe Automatic Drifting Devices for Locomotives, of which the following is a specification.

This device is so designed as to automatically admit a predetermined amount of 10 saturated steam through the super-heating units, when used on super-heating locomotives, or to the main valve chambers or the cylinders, and to automatically close off the same when the locomotive comes to a rest.

The objects of admitting steam under the above conditions are: first, to prevent the formation of a vacuum, which will also prevent induction of hot gases from the 15 front end extension into the steam cylinders and valve chambers, which causes carbonization of lubricant oil; second, to prevent the over-heating of super-heating units used with super-heating steam engines by the induction of hot gases from the fire box; third, to take up by degrees the momentum of reciprocating parts, especially on large 20 locomotives; and fourth, to prevent slack action in long trains by keeping train stretched until it is brought to rest.

In order that the invention may be better understood, reference is had to the accompanying drawing, forming a part of this 25 specification.

In the drawing a vertical sectional view of the appliance is shown.

Referring specifically to the drawing, 1 denotes a valve casing containing a passageway 2 one end 3 of which is connected 30 to a source of boiler steam supply, the connection being preferably made between the steam dome and the forward end of the boiler. The other end 4 of the passageway is connected with the engine cylinder. A 45 direct connection may be made; or a connection with the superheater header or the main valve chamber of the cylinder. Thus, it will be seen that saturated steam from the boiler enters the valve casing at 3, and 50 super-heated steam may enter at 4.

In the passageway 2 are two ported partitions provided with valves 5 and 6, respectively, the valve 5 being the first one from the end 3 of the passageway 2 and the 55 valve 6 being at the end 4. When these

valves are open, steam from the boiler is free to flow through the passageway from the end 3 to the end 4, and thence to the cylinder or other part to which the latter end is connected.

The valve casing 1 also has a chamber 7 in which is slidably mounted a controlling valve 8 having four heads defining three annular cavities or ports in the body of the valve, the same being indicated at 9, 10 and 11, respectively. The upper end of the valve 8 has a stem 12 around which is coiled a spring 13 which is held between the top of the valve and a nut 14 screwed into a cylinder 15 mounted on the valve casing 1 in line with the chamber 7, and forming 60 a guide for the upper end of the valve 8. The nut 14 is adjustable in the cylinder 15 to vary the tension of the spring 13. The outer end of the cylinder 15 is closed by a 65 cap 16.

The valve 5 is carried by a piston 17 slidably mounted in a bore 18 formed in the valve casing 1, and backed by a spring 19 held between the top of the piston and a 70 nut 20 closing the upper end of the bore. The end of the piston opposite the end engaged by the spring is exposed to the boiler pressure, the bore 18 opening at this end into the passageway 2. The piston has an 75 equalizing port 21.

The valve 6 is connected by a stem 22 to a valve 23 controlling a vent port 24 at one 80 end of a duct 25 in the valve casing, the other end of said duct leading from the 85 valve chamber 7. The valve 23 is backed by a spring 26 held between the top thereof and a screw plug 27 carried by the valve casing 1 in line with the port 24, the top of the valve also having a guide stem 28 90 working in a guide aperture in the plug.

In the valve casing 1 is also a duct 29 leading from the end 3 of the passageway 2 to one side of the valve chamber 7. A duct 30 leads from the bore 18, above the piston 17, to the other side of the chamber 7. The duct 30 has a branch 31 also leading to the chamber 7. From the end 4 of the passageway 2, above the valve 6, leads a by-pass 32, the same having a branch 33 which 100 leads to the bottom of the chamber 7. A small equalizing port 34 establishes communication between the passageway 2 beneath the valve 6, and the by-pass 32.

The end 4 of the passageway 2 has an 110

outlet 35 into a steam reservoir 36, said outlet being provided with a ball-check valve 37, and communicating with the passageway 2 beneath the valve 6 by a duct 38.

5 The valve casing 1 also has two small ports 39 for drain cocks.

The operation of the appliance is as follows:

Steam from the boiler enters the passageway 2 at 3 and is free to pass through the duct 29 to the valve cavity 10. Steam also passes to the under side of the piston 17 which is held down by its spring 19, and said piston holds the valve 5 to its seat. Steam 15 also passes through the equalizing port 21, and along the duct 30, and thence by way of the valve cavity 9 to the duct 25 to the valve 23 which is held to its seat by the spring 26 and the steam pressure. The steam 20 pressure on the ends of the piston 17 being balanced, the pressure of the spring 19 holds the piston down and the valve 5 closed. When the main throttle of the locomotive is 25 opened, superheated steam enters the passageway 2 at 4. This pressure opens the check valve 37 and steam flows quickly into the reservoir 36, and passes from the latter, through the duct 38 into the passageway 2 below the valve 6. The pressure on opposite 30 sides of the valve 6 is therefore equalized and it remains closed. The super-heated steam also passes by the way of the ducts 32 and 33 to the lower end of the valve 8, and when the pressure exceeds the tension of the 35 spring 13 which holds the valve down, said valve will rise until stopped by the stem 12 striking the cap 16. As the valve 8 rises, the cavity 9 no longer establishes communication between the ducts 30 and 25, and the 40 cavity 11 now laps the ducts 29 and 31, so that the boiler pressure is admitted through these ducts to the top or spring side of the piston 17. When the main throttle of the locomotive is closed, the check valve 37 prevents the steam from back flowing from the 45 reservoir 36 to the passageway 2, and the only outlet for this pressure is through the small port 34, so that an equal pressure is maintained on both sides of the valve 6 when 50 the same is seated after the locomotive comes to a standstill. The main throttle being closed, the pressure from the top of the valve 6 will escape much faster while the locomotive is moving than the pressure from 55 the reservoir 36 can escape through the port 34, so that the pressure below said valve will raise it from its seat, and as it is connected to the valve 23 the latter is also opened to allow the pressure in the duct 25 to escape 60 through the port 24 and by the way of the end 4 of the passageway 2, through the exhaust ports to the atmosphere. When the pressure under the valve 8 has reduced below 65 the tension of the spring 13, said valve is forced down by the spring, shutting off the

boiler pressure from the top of the piston 17, as the cavity 11 now does not connect the ducts 29 and 31, and connecting this pressure to the port 24 by the way of the port 21, and ducts 30 and 25. As the valve 70 23 is open, the pressure escapes into the passageway 2 resulting in a sudden drop of pressure on the upper end or spring side of the piston 17, so that the greater pressure under said piston raises the same against 75 the tension of the spring, and as the valve 5 is connected to the piston it rises off its seat. The valve 5 now being open, the boiler pressure passes from the end 3 of the passageway 2 to the valve 6, and as the latter is 80 now also open, it will be evident that saturated steam from the boiler can pass from the end 4 of the passageway to the engine cylinders, the valve 6 remaining open until the locomotive stops. When the pressure in 85 the main valve chamber or in the cylinders exceeds the tension of the spring 13, the valve 8 again rises, shutting off the port 24 from the upper or spring end of the piston 17, and cutting in the boiler pressure on said 90 end of the piston, and as the pressure is now equalized on both ends of the piston, the spring 19 forces the piston down and closes the valve 5, thus shutting off steam from the boiler to the cylinders. 95

I claim:

1. A drifting valve appliance comprising a passage establishing communication between a source of saturated steam and the engine independent of the main steam supply thereof, a valve mechanism controlling the passage, a reservoir having a supply connection with the pressure at the outlet end of the passage, and a means for permitting an opening movement of the aforesaid 100 valve mechanism, said means including a valve which closes the passage when seated, and is exposed on one side to the pressure in the reservoir and on the other side to the pressure in the outlet end of the passage, 105 and a controlling valve for said means subject to and actuated by the steam pressure in the outlet end of the passage.

2. A drifting valve appliance for locomotives comprising a passage establishing communication between a source of saturated steam and the engine independent of the main steam supply thereof, a valve mechanism controlling the passage, and a means for permitting an opening movement of said 115 valve mechanism, said means including a valve which closes the passage when seated, and which is, during the time the locomotive is running under steam, exposed on both sides to the pressure in the outlet end of the 120 passage, and a controlling valve for said means subject to and actuated by the steam pressure in the outlet end of the passage.

3. A drifting valve appliance comprising a casing having a passageway which is con- 125

nected at one end to a source of saturated steam, and at the other end to the engine independent of the main steam supply thereof, a valve controlling the passageway, a piston connected to said valve, a second valve in the passageway, a vent valve connected to said second valve, and a steam actuated controlling valve subject to the pressure at the second mentioned end of the passageway, and having means for establishing and breaking communication between the back of the piston and the first mentioned end of the passageway, and also between the back of the piston and the vent valve.

4. A drifting valve appliance comprising a casing having a passageway which is connected at one end to a source of saturated steam, and at the other end to the engine independent of the main steam supply thereof, a valve controlling the passageway, a piston connected to said valve, a second valve in the passageway, a vent valve connected to said second valve, a steam actuated controlling valve subject to the pressure at the second mentioned end of the passageway, and having means for establishing and breaking communication between the back of the piston and the first mentioned end of the passageway, and also between the back of the piston and the vent valve, and a spring resisting the steam pressure on the controlling valve.

5. A drifting valve appliance comprising a casing having a passageway which is connected at one end to a source of saturated steam, and at the other end to the engine independent of the main steam supply thereof, a valve controlling the passageway, a piston connected to said valve a second valve in the passageway, and exposed on both sides to the pressure at the second mentioned end thereof, a vent valve connected to said second valve, and a steam actuated controlling valve subject to the pressure at the second mentioned end of the passageway, and having means for establishing and breaking communication between the back of the piston and the first mentioned end of the passageway, and also between the back of the piston and the vent valve.

6. A drifting valve appliance comprising a casing having a passageway which is connected at one end to a source of saturated steam, and at the other end to the engine independent of the main steam supply thereof, a valve controlling the passageway, a piston connected to said valve, a second valve in the passageway, a vent valve connected to said second valve, a steam actuated controlling valve subject to the pressure at the second mentioned end of the passageway, and having means for establishing and breaking communication between the back of the piston and the first mentioned end of the passageway, and also between the back of the

piston and the vent valve, a reservoir connected to the second mentioned end of the passageway and having an outlet to one side of the second mentioned valve, the other side of said valve being exposed to the pressure in the second mentioned end of the passageway, and an equalizing port between the opposite sides of the valve.

7. A drifting valve appliance comprising a casing having a passageway which is connected at one end to a source of saturated steam, and at the other end to the engine independent of the main steam supply thereof, a valve controlling the passageway, a piston connected to said valve, a second valve in the passageway, a vent valve connected to said second valve, a steam actuated controlling valve subject to the pressure at the second mentioned end of the passageway, and having means for establishing and breaking communication between the back of the piston and the first mentioned end of the passageway, and also between the back of the piston and the vent valve, a reservoir connected to the second mentioned end of the passageway and having an outlet to one side of the second mentioned valve, the other side of said valve being exposed to the pressure in the second mentioned end of the passageway, an equalizing port between the opposite sides of the valve, and a check valve at the inlet to the reservoir.

8. A drifting valve appliance comprising a casing having a passageway which is connected at one end to a source of saturated steam, and at the other end to the engine independent of the main steam supply thereof, a valve controlling the passageway, a piston connected to said valve, a second valve in the passageway, a vent valve connected to said second valve, a steam actuated controlling valve subject to the pressure at the second mentioned end of the passageway, and having means for establishing and breaking communication between the back of the piston and the first mentioned end of the passageway, and also between the back of the piston and the vent valve, and a spring engaging one side of the piston.

9. A drifting valve appliance comprising a casing having a passageway which is connected at one end to a source of saturated steam, and at the other end to the engine independent of the main steam supply thereof, a valve controlling said passageway, a piston connected to said valve and having an equalizing port, a spring for moving the piston in a direction to close the valve, a second valve in the passageway, a vent duct leading from one side of the piston and having an outlet into the second mentioned end of the passageway, a valve for said outlet connected to the second mentioned valve, a controlling valve for admitting steam from the first mentioned end of the passageway to the

back of the piston, said valve also establishing and breaking communication between the back of the piston and the aforesaid vent outlet, a chamber in which the controlling valve is slidably mounted, one end of the chamber being connected to the second mentioned end of the passageway, a spring forcing the controlling valve in the direction of the last mentioned end of the chamber, a reservoir connected to the second mentioned end of the passageway and having an outlet to one side of the second mentioned valve, and an equalizing port from said side of the valve to its opposite side.

15 10. A drifting valve appliance comprising a casing having a passageway which is connected at one end to a source of saturated steam, and at the other end to the engine independent of the main steam supply

20 thereof, a valve controlling said passageway, a piston connected to said valve and having an equalizing port, a second valve in the passageway, a vent duct leading from one side of the piston and having an outlet

25 into the second mentioned end of the passageway, a valve for said outlet connected to the second mentioned valve, a controlling valve for admitting steam from the first mentioned end of the passageway to the back of

30 the piston, said valve also establishing and breaking communication between the back of the piston and the aforesaid vent outlet, a chamber in which the controlling valve is slidably mounted, one end of the chamber

35 being connected to the second mentioned end of the passageway, a spring forcing the controlling valve in the direction of the last mentioned end of the chamber, a reservoir connected to the second mentioned end of the

40 passageway and having an outlet to one side of the second mentioned valve, and an equalizing port from said side of the valve to its opposite side.

11. A drifting valve appliance comprising
45 a casing having a passageway which is connected at one end to a source of saturated steam, and at the other end to the engine independent of the main steam supply thereof, a valve controlling said passageway, a piston
50 connected to said valve and having an equalizing port, a second valve in the passageway, a vent duct leading from one side of the piston and having an outlet into the second mentioned end of the passageway, a valve
55 for said outlet connected to the second mentioned valve, a controlling valve for admitting steam from the first mentioned end of the passageway to the back of the piston, said valve also establishing and breaking
60 communication between the back of the piston and the aforesaid vent outlet, a chamber in which the controlling valve is slidably mounted, one end of the chamber being connected to the second mentioned end of
65 the passageway, a spring forcing the con-

trolling valve in the direction of the last mentioned end of the chamber, a reservoir connected to the second mentioned end of the passageway and having an outlet to one side of the second mentioned valve, an equalizing port from said side of the valve to its opposite side, and a check valve at the inlet to the reservoir. 70

12. A drifting valve appliance comprising a casing having a passageway which is connected at one end to a source of saturated steam, and at the other end to the engine independent of the main steam supply thereof, a valve controlling said passageway, a piston connected to said valve and having an equalizing port, a second valve in the passageway, a vent duct leading from one side of the piston and having an outlet into the second mentioned end of the passageway, a valve for said outlet connected to the second mentioned valve, a controlling valve for admitting steam from the first mentioned end of the passageway to the back of the piston, said valve being subject to the pressure at the second mentioned end of the passageway and also establishing and breaking communication between the back of the piston and the aforesaid vent outlet, and a spring resisting such pressure.

13. A drifting valve appliance comprising 95
a casing having a passageway which is con-
nected at one end to a source of saturated
steam, and at the other end to the engine in-
dependent of the main steam supply thereof,
a valve controlling said passageway, a pis-
ton connected to said valve and having an 100
equalizing port, a second valve in the pas-
sageway, a vent duct leading from one side
of the piston and having an outlet into the
second mentioned end of the passageway, a 105
valve for said outlet connected to the second
mentioned valve, and a controlling valve for
admitting steam from the first mentioned
end of the passageway to the back of the
piston, said valve being subject to the pres-
sure at the second mentioned end of the pas-
sageway and also establishing and breaking
communication between the back of the pis-
ton and the aforesaid vent outlet. 110

14. A drifting valve appliance comprising 115
a casing having a passageway which is con-
nected at one end to a source of saturated
steam, and at the other end to the engine in-
dependent of the main steam supply thereof,
a valve controlling said passageway, a pis-
ton connected to said valve and having an 120
equalizing port, a second valve in the pas-
sageway, a vent duct leading from one side
of the piston and having an outlet into the
second mentioned end of the passageway, a
valve for said outlet connected to the second 125
mentioned valve, a controlling valve for ad-
mitting steam from the first mentioned end
of the passageway to the back of the piston,
said valve being subject to the pressure at 130

- the second mentioned end of the passageway and also establishing and breaking communication between the back of the piston and the aforesaid vent outlet, a reservoir 5 connected to the second mentioned end of the passageway and having an outlet to one side of the second mentioned valve, and an equalizing port from said side of the valve to its opposite side.
- 10 15. A drifting valve appliance comprising a passage establishing communication between a source of saturated steam and the engine independent of the main steam supply thereof, a valve mechanism controlling the passage, a reservoir having a supply connection with the outlet end of the passage, and a means for permitting an opening movement of the aforesaid valve mechanism, said means including a valve which closes the passage when seated, and is exposed on one side to the pressure in the reservoir and on the other side to the pressure in the outlet end of the passage.
- 15 20 25 30 35 40 16. A drifting valve appliance comprising a passage establishing communication between a source of saturated steam and the engine independent of the main steam supply thereof, a valve mechanism controlling the passage, a reservoir having a supply connection with the outlet end of the passage, a check valve in said supply connection, and a means for permitting an opening movement of the aforesaid valve mechanism, said means including a valve which closes the passage when seated, and is exposed on one side to the pressure in the reservoir and on the other side to the pressure in the outlet end of the passage.
17. A drifting valve appliance comprising a passage establishing communication between a source of saturated steam and the engine independent of the main steam supply thereof, a valve mechanism controlling the passage, a reservoir having a supply connection with the outlet end of the passage, a check valve in said supply connection, and a means for permitting an opening movement of the aforesaid valve mechanism, said means including a valve which closes the passage when seated, and is exposed on one side to the pressure in the reservoir and on the other side to the pressure in the outlet end of the passage.
18. A drifting valve appliance comprising a passage establishing communication between a source of saturated steam and the engine independent of the main steam supply thereof, a valve mechanism controlling the passage, a reservoir having a supply connection with the pressure at the outlet end of the passage, a check valve in said supply connection, and a means for permitting an opening movement of the aforesaid valve mechanism, said means including a valve which closes the passage when seated, and is exposed on one side to the pressure in the reservoir and on the other side to the pressure in the outlet end of the passage.
19. A drifting valve appliance comprising a passage establishing communication between a source of saturated steam and the engine independent of the main steam supply thereof, a valve mechanism controlling the passage, and a means for permitting an opening movement of the aforesaid valve mechanism, said means including a valve which closes the passage when seated, and is normally exposed on both sides to the pressure in the outlet end of the passage.
